UNITED STATES PATENT OFFICE.

EDGAR L. YORK, OF PEORIA, ILLINOIS, ASSIGNOR TO YORK IRONER AND APPLIANCE COMPANY, OF BEARDSTOWN, ILLINOIS, A CORPORATION OF ILLINOIS.

IRONING MACHINE.

Application filed September 8, 1924. Serial No. 736,385.

My invention relates more particularly to ironing machines for use in households where it is desirable that the machine be small and light so that it may be easily moved from place to place and stored away when not in use.

One object of my invention is to mount the motor for the machine on a removable bracket, which also carries a part of the driving gearing, to the end that these parts of the machine which constitute considerable of the weight of the machine may be easily removed from it when it is desired to move the machine from place to place.

Another object of my invention is the provision of mechanism whereby the gearing between the motor and the ironing cylinder or roll may be thrown out of engagement when the shoe is moved out of contact with the roll.

Another object of my invention is the provision of suitable means for moving the shoe into and out of ironing position with relation to the roll, and controlling the movement of the shoe by means of a suitable device located within easy reach of the operator.

Other objects of my invention will appear and be described in the specification.

The novelty of my invention will be hereinafter more fully set forth and specifically pointed out in the claims.

In the accompanying drawings:

Fig. 1, Sheet 1, is an end view of a machine embodying my invention.

Fig. 2, Sheet 2, is a rear view of the machine, some of the parts being broken away because of the length of the machine.

The same numerals of reference are used to indicate identical parts in both figures.

As illustrated one form of machine embodying my invention though without limiting myself to the precise details of construction or the arrangement of parts shown but availing myself of all equivalents and modifications which may be used or made and which come within the scope of the appended claims, I have shown a machine comprising the various parts and arrangements, I will now describe.

Upon a suitable base-board 1 the end members 2 and 3 are mounted, the end member 2 being at the right end of the machine when viewed from the front, and the end mem-

ber 3 at the left end of the machine. The upper forwardly projecting portion of each of these end members 2 and 3 carries the feed board 4, these parts comprising the main frame work of the machine.

The ironing roll 5 is mounted between the frame members 2 and 3 and is driven by a gear 6 shown in dotted lines in Fig. 1, the gear being enclosed in a housing 7 formed as a part of the end member 2.

A pin 8 is carried by the frame member 2 and the motor bracket 9 is mounted on this pin, the mounting being such that when desired the motor bracket may be moved endwise of the pin and disengaged therefrom.

The motor bracket 9 carries the motor 10, and the motor, through the coupling 11 drives the worm shaft 12 which carries the worm 13, the latter meshing with and driving a worm wheel 14, both of these parts being enclosed in a gear housing 15 formed as a part of the motor bracket 9. The shaft 16 of the worm wheel 14 extends through the gear housing and is formed as a pinion 17, shown in dotted lines in Fig. 1, which projects through the slotted opening 18 in the cover of the gear housing 7 of the end frame 2, and engages with and drives the gear 6 when the machine is operating.

A pair of arms 19 are pivotally mounted near the base-board 1 and project upwardly and carry the ironing shoe 20, the latter being of any suitable construction and provided with any suitable heating element such as a gas heater or an electric heater, whereby the ironing shoe may be brought to the proper temperature for ironing.

About midway of the length of the shoe 20, the moving mechanism for the shoe is mounted, and this mechanism consists of a toggle connection, the upper end being attached as at 21 to the bracket 22 which is fastened to the shoe, and the lower end being attached as at 23 to the bracket 24 which is attached to the base-board 1.

The toggle connection comprises the lower adjustable portion 25, by means of which the length of the toggle may be properly adjusted and the upper spring pressure portion 26, this latter portion comprising a rod 27, spring 28, adjusting handwheel 29, and upper yoke 30. The rod 27 is headed as at 31, the head lying within the throat of the yoke and standing slightly clear thereof when un-

der pressure for operation, the head serving to pull the shoe back away from the roll when the toggle pressure device is moved.

A movable frame is mounted across the front of the machine and consists of a pair of end members 32, pivoted as at 33 to the base-board 1 and connected together by a slat or board 34. A rod 35 is mounted at each end of this movable frame and carries a ball 36 at its upper end the latter serving as a handle to move the frame on its pivots. The right end of this frame carries a boss 37, the latter serving as a mounting for the connecting rod 38 which extends rearwardly and is connected to the upper end of a crank 39 mounted on a square shaft 40 which is suitably mounted in an extension of the end frame 2 at one end and in the bracket 24 at the center of the machine. A second crank 41 similar to crank 39 is carried by the shaft 40, and the upper end of this crank connects with the toggle mechanism by means of a link 42.

The movable frame at the forward portion of the machine carries a stop 43 to limit its movement towards the rear, in this way providing a rearward movement limit for the toggle pressure mechanism for the shoe.

The end of the shaft 40 which projects to the right of the right frame member 2, carries a cam 44 which rests against a portion of the motor bracket 9 as shown more clearly in Fig. 1.

The left frame member 3 is deeply throat-ed as at 45, Fig. 2, to permit certain classes of work to be passed through the machine, and giving the effect of an open end machine, this effect being called a ruffler.

The operation of the machine is as follows: The parts as shown are in proper position when the machine is in operation. To disengage the shoe from the roll, the operator moves the movable front frame by means of the ball handles 36, by moving these balls away from the feed board 4. This rocks the square shaft 40, breaks the toggle pressure device for the shoe, and moves the shoe rearwardly about the lower pivots of the levers 19. At the same time the cam 44 coming in contact with the motor carrying portion of the bracket 9, rocks the bracket about the center of the pin 8 and moves the pinion 17 out of engagement with the gear 6, the pinion traveling down in the slot 18, in this way disconnecting the roll 5 from the motor 10. The parts are now in proper position to heat the iron and prepare for operation of the machine.

When the shoe has been properly heated, and the work to be ironed spread upon the feed board, and the motor started, the operator moves the balls 36 up to the position of Fig. 1 and this movement permits the weight of the motor to become effective to cause the engagement between the gearing,

to start the roll rotating, and also brings the shoe into contact with the roll and subjects it to the pressure of the spring 28. This pressure may be adjusted as desired by moving the handwheel 29 which is threaded upon the rod 27 so that heavy or light goods may be properly handled by the machine.

When the work has been finished and it is desired to move the machine to a place of storage, the motor and its bracket and associated parts can be first taken from the machine by sliding the bracket off of the pin 8, in this way removing a large part of the weight of the machine, and so reducing the total weight of the machine that the balance can be easily handled.

When ironing the collars and cuffs of shirts and other classes of work, the operator stands at the left end of the machine and uses the throat 45 of the bracket 3 to pass the work through.

Having thus fully described my invention, I claim:

1. In an ironing machine the combination of a roll, a shoe, a movable mounting for the shoe, driving mechanism for the roll, a motor for the driving mechanism, a bracket carrying the motor and a portion of the driving mechanism, means for moving the shoe into and out of ironing position, and means operated by the movement of the shoe moving means for moving the motor bracket to move the portion of the driving mechanism which it carries out of engagement with the rest of the driving mechanism.

2. In an ironing machine the combination of a roll, driving mechanism therefor, a motor for the driving mechanism, a bracket carrying the motor and a portion of the driving mechanism, a shoe for the roll, means for moving the shoe into and out of ironing position and means moved by the movement of the shoe moving means for moving the motor bracket to disengage the driving mechanism when the shoe is moved out of ironing position.

3. In an ironing machine the combination of a roll, driving mechanism therefor, a motor for the driving mechanism, a pivoted bracket upon which the motor and a part of the driving mechanism is mounted, means operated by the movement of a shoe moving means for swinging the bracket to disengage that part of the driving mechanism which it carries from the balance of the driving mechanism, a shoe, and means for moving the shoe into and out of ironing position.

4. In an ironing machine the combination of a roll, driving mechanism therefor, a motor for the driving mechanism, a pivoted bracket for the motor and carrying a part of the driving mechanism, a shoe for the roll, toggle operated pressure means for moving the shoe into and out of operating position, and means connected for operation

with the toggle operated pressure means for swinging the motor bracket to disconnect the roll driving gearing when the shoe is moved out of ironing position and to permit 5 the re-engagement of the driving mechanism when the shoe is moved into ironing position.

5. In an ironing machine the combination of a roll, driving mechanism therefor, a 10 motor for the driving mechanism, a movable

bracket for the motor and carrying a portion of the driving mechanism, a shoe, and an adjustable toggle for moving the shoe into and out of ironing position, spring pressure mechanism to hold the shoe yieldingly 15 in operating position, means for moving the toggle pressure mechanism said means also moving the motor bracket to engage or disengage the driving connection.

EDGAR L. YORK.
